UNITED STATES PATENT OFFICE.

WILLIAM MELLOR, OF SEBRING, OHIO.

PORCELAIN-KILN.

1,275,285.

Specification of Letters Patent. Patented Aug. 13, 1918.

Application filed March 30, 1918. Serial No. 225,692.

To all whom it may concern:

Be it known that I, WILLIAM MELLOR, a citizen of the United States, residing at Sebring, in the county of Mahoning and State of Ohio, have invented a new and useful Porcelain-Kiln, of which the following is a specification.

My invention relates to porcelain kilns and more particularly to those designed for 10 firing porcelain ware and the like during the decorating process of the same, the purpose being to construct a kiln of this type that will distribute the heat generated in the fire boxes evenly throughout all parts of the 15 kiln.

Another object is to construct a kiln in which a perfectly even heat can be maintained during the time of firing the ware, thus enabling the user to produce a more 20 perfectly finished article of ware.

Another object is to arrange the flue passages in such a way that all of the heat generated will come in close contact with the inner compartment walls, thereby materially 25 reducing the amount of fuel necessary to generate a given heat.

Another object is to reduce the amount of labor necessary in keeping the fire under my kiln owing to the less amount of fuel necessary. 30

A further object is to simplify the construction of this class of kilns, and thereby reduce the cost of installing the same.

With these objects in view the invention 35 consists in the novel construction and arrangement of parts, hereinafter described, illustrated in the accompanying drawings, and particularly pointed out in the appended claims, it being understood that various changes in the form, proportions, size 40 and minor details of construction may be made within the scope of the appended claims, without departing from the spirit or sacrificing any of the advantages of the 45 invention.

In the drawings:

Figure 1 is a cross sectional view of my kiln taken on a line through one of the fire boxes.

Fig. 2 is a horizontal section taken just above the line of the floor of the inner chamber of my kiln and with a portion of the brick arches over the fire boxes shown in section.

Similar numerals of reference indicate

corresponding parts throughout the several figures of the drawings.

The heating chamber or interior of my kiln is constructed with fire clay or tile walls and floor and is indicated at 1, the usual door 2 gives access to this heating chamber. Spaced from the walls of the heating chamber 1 is the brick outer shell 4 and beneath the floor of this chamber are rows of fire clay tiles forming pillars 5, which are arranged to leave passages 6 extending longitudinally of the kiln and cross passages 7 running transversely therebetween. Partition walls 8 extending from the outer shell 4 to the walls of the heating chamber 1 divide the space between the said walls into a series of passages or flues 9 which are arranged to communicate with the lateral passages 7. A series of fire boxes 10 are located at one side of the kiln and beneath the level of the floor of the heating chamber 1, as clearly shown in Fig. 1, each of the fire boxes 10 being in direct communication with one or more of the cross flues 7. A stack 11 is arranged at the center of the top of the kiln and is divided by a partition 12 extending upwardly from the top of the heating chamber. The partition 12 extends the entire width of the stack, the result being that a separate draft is drawn upwardly upon each side of the heating chamber through the flues 9. This peculiar arrangement of the flues will cause the flame traveling from the fire boxes to spread over approximately the entire surface of the bottom of the kiln. In kilns of ordinary construction the flues at either side, such as the flues 9 in my kiln, are joined at the top and enter the stack as one passage. The result of this construction is that the draft will be strongest on the side next the fire boxes or in the event the fire boxes are located directly beneath the kiln the flues on one side will always tend to draw the heaviest flame, thus heating the kiln unevenly and requiring the burning of additional fuel to raise the temperature of the underheating side of the kiln to the proper point.

In my construction the partition at the top of the kiln at the point where the flues enter the stack creates a separate draft for each side of the kiln and by so doing draws the flame evenly and thoroughly over every portion of the heating chamber surface. I am thus enabled to maintain an even heat with-

in the kiln with a minimum consumption of fuel which is not only an economy in fuel but requires less time to fire. Actual test on a number of these kilns which I now have 5 in operation has proven that the same or a greater amount of ware can be fired in a kiln constructed according to my invention, than can be fired in the ordinary kiln and with a saving of fifty to sixty per cent. of the 10 amount of coal used in the ordinary kiln.

Although the drawings and above specification disclose the best mode in which I have contemplated embodying my invention I desire to be not limited to the details of such 15 disclosure, for, in the further practical application of my invention, many changes in form and construction may be made, as circumstances require or experience suggests, without departing from the spirit of the invention, within the scope of the appended 20 claims.

Having fully described my invention what I claim as new and desire to secure by Letters Patent, is—

25 1. A kiln of the character described having a heating chamber, a plurality of fire boxes beneath said heating chamber and at one side thereof, a plurality of lateral flues communicating with said fire boxes, a plurality of substantially vertical flues upon one 30 side of said heating chamber and communicating with said lateral flues and a plurality of substantially vertical flues upon the other side of said heating chamber and connected 35 with said lateral flues and a separate stack for the vertical flues upon each side of said heating chamber.

40 2. A kiln of the character described, comprising a heating chamber, a plurality of fire boxes disposed beneath said heating chamber and at one side thereof, a plurality of flues communicating with each of said fire boxes and extending laterally beneath said heating chamber, a plurality of flues ex- 45 tending longitudinally beneath said heating chamber and communicating with each of said lateral flues, a substantially vertical flue

extending upwardly at either end of said lateral flues, all of said vertical flues upon one side of the heating chamber entering one 50 stack above the top thereof and all of the said vertical flues on the other side of the heating chamber entering another stack adjacent the said first stack.

55 3. In a kiln of the character described, a heating chamber, a plurality of fire boxes in a plane beneath the floor of said heating chamber at one side thereof, a plurality of flues communicating with each of said fire boxes and extending laterally beneath the 60 said floor, a plurality of flues extending longitudinally beneath said floor and joining all of said lateral flues, a vertical flue extending upwardly from either end of each of said lateral flues, all of said vertical flues entering 65 a stack at the top of said kiln, a partition arranged longitudinally of said stack and separating all of the vertical flues upon one side of the kiln from all of the vertical flues upon the other side thereof. 70

4. A kiln of the character described, comprising a heating chamber or inner compartment and an outer shell, a plurality of fire boxes disposed beneath said heating chamber, flues communicating with said fire boxes and extending laterally beneath the floor of said heating chamber, a vertical flue extending upwardly from one end of each of said lateral flues, the said vertical flues being intermediate the heating chamber and outer 75 shell, a vertical flue extending upwardly from the other end of each of said lateral flues and intermediate the said heating chamber and outer shell, a stack opening through the top of said outer shell, all of the 80 vertical flues entering said stack and a partition arranged longitudinally of said kiln and within said stack and separating all of the vertical flues upon one side of said kiln from all of the vertical flues upon the other 85 side thereof. 90

In testimony that I claim the above, I have hereunto subscribed my name.

WILLIAM MELLOR.
